CARBURETORS

Robert E. Williams, Waynesburg, Pa.
(1607 Lower Silver Lake Road, Topeka, Kans. 66608)
Filed May 26, 1966, Ser. No. 553,071
1 Claim. (Cl. 123—134)

This invention relates to carburetors for internal combustion engines and more specifically to a device whereby the air is mixed with the fuel in a highly combustible and economical manner.

Aside from the conventional jet type carburetor which sprays the fuel directly into the air, other types of carburetors have all employed means for vaporizing the fuel by various methods; such as, injecting compressed air into the fuel; heating the fuel and collecting the vapors, etc.

This invention is new and different in that it converts raw fuel and air into a highly vaporized and combustible mixture by the action of the air passing through the fuel without the assistance of heat, compressed air or other mechanical or chemical means.

It is widely known among those skilled in the art that the conventional jet type carburetor produces fair performance over a wide speed range of the engine but also due to the inefficient droplets of gasoline which are not converted to vapor, there is the disadvantage that much of the fuel is never converted into enough of a vapor to burn properly. As these larger droplets of fuel are unburned they cause unnecessary wear on the cylinder walls due to their tendency to "wash off" any oil film which should be present for proper lubrication of the cylinder.

An object of my invention is to produce a highly combustible vapor whereby there will be no appreciable waste of fuel nor unnecessary wear of the engine due to unburned fuel particles.

Another object of this invention is to provide a highly efficient means of converting gasoline into a vaporous state with air without the use of complicated linkages, venturis, or jets.

Another object of my invention is that due to the simplicity of design it can be easily and economically manufactured. The mechanical simplicity assures the carburetor of trouble free performance and longevity of operation.

Still a further object of my invention is that the air which is drawn into the fuel does not have to be filtered. Any foreign matter in the air such as dust, dirt, and most impurities remain suspended in the gasoline and are not drawn into the vapor. Any large accumulation of foreign matter is easily removed by taking off the top of the carburetor and cleaning the residue from the body.

And still another object of this invention is that should a fire or back fire occur within the intake manifold of the engine, the flame produced is not able to travel past the flame arrester and into the fuel which is held in the body of the carburetor.

Still a further object of my invention is to provide a carburetor which can easily be adapted to engines which employ any type of a carburetor; whether side draft, down draft, or up draft.

This invention and its operation can easily be understood by reference to the attached drawing of which:

FIGURE 1 is a cross sectional side view of the entire carburetor assembly.

FIGURE 2 is a top view of the cover plate and attached air tubes.

FIGURE 3 is a top view of the fine mesh wire screen or flame arrester which presents a fire from entering the carburetor vapor area.

Referring now to FIGURE 1; as the throttle valve 7 is moved out of the closed position as shown, the low pressure created by the intake cycle of an internal combustion

2

engine is admitted into area 16, past the flame arrester 5, and into the vapor chamber 2. This low pressure causes atmospheric air to be drawn into the carburetor body through the air tubes 8 which are attached to the cover plate 1. In order that the air be admitted into the vapor chamber 2, it must first pass through the fuel 4 in the form of bubbles. These air bubbles mix with the gasoline as they rise from the bottom of the air tubes 8 to the top of the fuel level. The vapor created by this action is then drawn past the flame arrester 5, into area 16, thence past the throttle valve 7 and into area 15 which is bolted to the intake manifold of the engine by the base of the carburetor 14. Upon leaving area 15 the fuel air vapor passes into the cylinders by way of the intake manifold (not shown).

The fuel level 4 is held at a constant level within the body 3 by means of a conventional float valve 6 and float 12. The fuel is admitted into the valve 6 by a small diameter fuel line 10. Pressure is applied to the fuel in line 10 by means of an external fuel pump (not shown) or by a gravity feed system (not shown).

FIGURE 2 shows the top of the cover plate 1 which is attached to the body 3 by bolts 17. The bolts 17 are secured to the body 3 by protruding lugs 11 which are welded or cast onto the body. An air-tight gasket 18 is located between the cover plate 1 and the body 3 to insure an airtight seal between the atmosphere and the vapor chamber 2.

The body 3 and the cover plate 1 are made of steel or of a metal which is easily cast. The air tubes 8 are made of brass and secured to the cover plate 1 by means of brazing or any suitable manner to assure an airtight seal.

A flame arrester 5 is shown in FIGURE 3. This safety device is secured by means of a screw to the top of the pipe extending up through the fuel. The inside of the pipe forms areas 15 and 16 plus it acts as a means of attachment for the throttle valve 7. This pipe is an integral part of the body 3.

Should a fire occur within the engine or the intake manifold it cannot reach the vapor chamber 2 due to the fine mesh wire screen (flame arrester 5). Flame or fire will not pass through a screen of an extremely fine mesh; however, the fuel air vapors are readily and easily admitted without restriction.

It is possible that minor changes in size, detail and arrangements coming within the field of invention may be adopted in practice.

Having thus described my invention what I claim is:

A carburetor for supplying a fuel air mixture to be burned comprising enclosed chamber means for holding a supply of liquid fuel, said chamber means including a bottom wall having a central opening therein, an upstanding peripheral side wall, and a removable top wall having a plurality of inlet openings therein, means for supplying liquid fuel to said chamber, means for regulating the fuel supplied to said chamber means for maintaining a selected upper level of liquid fuel above said bottom wall, a fuel air conduit for delivering a fuel air mixture to be burned and projecting upwardly into said chamber means through said central opening in said bottom wall, said conduit having an open upper end spaced above said selected upper level of liquid fuel in said chamber means and below said top wall and an open lower end adapted for connection with the intake manifold of an internal combustion engine, throttle valve means in said conduit below said chamber means for controlling the flow of fuel air mixture to said engine, screen means mounted across the upper open end of said conduit, and a plurality of spaced apart, air supply tubes for directing air into the liquid fuel in said chamber means, said tubes being equally spaced around said conduit and supported by said top wall, each of said tubes including an open upper

end in communication with the atmosphere through one of said inlet openings in said top wall and an open lower end spaced beneath the selected upper level of fuel in said chamber means whereby combustion air is drawn downwardly through said tube from the atmosphere into said liquid fuel and rise upwardly therein before flowing downwardly through said conduit for combustion.
